ENGINE STARTING MECHANISM

Romeo M. Nardone, East Orange, N. J., assignor,
by mesne assignments, to Eclipse Aviation Corporation,
East Orange, N. J., a corporation of
New Jersey

Application November 30, 1931, Serial No. 578,163

7 Claims. (Cl. 121—37)

This invention relates to starting devices for internal combustion engines.

One of the objects of the invention is to provide an engine starter of the rotation producing type embodying novel means for producing engagement with and rotation of a member of the engine to be started.

A further object of the invention is to provide in a starting device of the foregoing character, 10 novel means for converting an axially directed pressure into a rotation producing force whereby the axial movement of the driving member is translated to the engine cranking member.

A further object of the invention is to provide 15 a novel starting mechanism of the type employing a plurality of power actuated members one of which operates to produce engagement between the starting mechanism and a member of the engine to be started, and another of which operates to impart a cranking torque to the engine engaging member.

Other objects and advantages to be derived 20 from the use of the invention reside in the specific construction, combination and inter-relation of parts whereby a compact, efficient and easily operated and maintained unit is produced, all of which objects and advantages will appear 25 more clearly upon an inspection of the following specification, with reference to the accompanying drawings illustrating the preferred embodiment of the invention. It is to be expressly understood however that the said drawings are 30 for the purpose of illustration only and are not to be construed as a definition of the limits of the invention, reference being had to the appended claims for this purpose.

Referring to the drawings, wherein like reference characters refer to like parts throughout the several views:

40 Fig. 1 is a longitudinal axial section through a device embodying the invention;

Fig. 2 is a transverse sectional view taken along the line 2—2 of Fig. 1; and

Fig. 3 is a view at right angles to the viewpoint 45 of Fig. 1, the view being taken along the line 3—3 of Fig. 1.

Fig. 4 is similar to Fig. 1 but showing the device in a partly operated position.

Referring to the drawings, and particularly to 50 Fig. 1, the invention is shown embodied in a substantially cylindrical self-contained unit, the casing of which is composed of a plurality of interlocked casing sections, the first section 5 being provided with a flange 6 having apertures 7 through which may be inserted suitable fasten-

ing means engaging a corresponding flange 8 on the engine crankcase. At its outer end, the section 5 is formed to provide a suitable surface for reception of the intermediate section 10, the said section 10 being secured to the section 5 by suitable means 12. The outer end of section 10 is threaded, as indicated at 13, for reception of the correspondingly threaded end portion 14 of the outer casing section 15, the latter being integral with a head 16.

In order to seal the starting mechanism against entry of oil from the crankcase 8, a baffle member 27 having a combined cylindrical and frustoconical shape is provided between the crankcase 8 and the engine engaging member 25. As shown 70 in this baffle member 27 has an outwardly directed flange 28 adapted to be held in place between the flanges 6 and 8 by the fastening means passing through the apertures 7, and is further provided with an inwardly directed rim or flange 29, 75 the inner circular edge of which is turned to point outwardly, thus forming a semi-circular concave ledge or lip 30.

The novel power actuated mechanism for moving the engine engaging member 25 into operative position and thereafter cranking the engine, comprises a piston 37 fitting the interior cylindrical surface of the casing section 15 and preferably provided with piston rings 38 insuring fluid tight registry with said surface. As 80 shown the piston has a centrally disposed extension or hub 39, the bore of which is threaded, as indicated at 40, for cooperation with a correspondingly externally threaded shaft 42, the latter also having a central bore 43, said central 85 bore being adapted to receive a bearing sleeve 44 facilitating relative rotation between screw shaft 43 and the elongated hub 45 of the engine engaging member 25. The shaft 42 flares outwardly to form a gear, to be further described, the outwardly extending portion forming an annular ledge 46 adapted to receive a grooved washer 47 constituting an abutment for a coiled compression spring 48, the opposite end of which 90 abuts a thrust bearing 50 engaging a hub portion 51 of the piston extension 39. The coil spring 48 thus serves to normally maintain the piston 37 in the position shown in Fig. 1, from which position it is adapted to be moved in response to admission of pressure fluid in the 95 manner to be described.

The means for holding the piston 37 from rotation and thus causing positive rotation of the screw shaft 42 in response to axial motion of the piston, preferably comprises a plurality of 100

splines or equivalent longitudinally extending ribs 53 provided at regularly spaced intervals about the inner circumference of the casing 15 and a corresponding number of teeth or splines 54 extending radially outward at corresponding intervals on the end surface 55 of the web or skirt 56 integral with the hub 51 above referred to. With this construction it is apparent that piston 37, sleeve 39 and skirt 56 may move forward as a unit along the inner surface of the casing 15, but cannot rotate relatively thereto.

The novel means for producing first, an axial movement of the engine engaging member 25, and thereafter a rotary movement thereof in response to the rotation of screw shaft 42, comprises an annular gear 65 which as above noted, is preferably integral with screw shaft 42, and adapted to mesh with a plurality of (as shown three) idler gears 69, the latter being mounted on shafts 70 held in position in bored holes in the housing section 5, shaft 70 having shoulders 71 to prevent them from inward movement. The idler gears 69 are held to the shaft 70 by suitable means including preferably a ring 72 and screws 73, and each of the gears is adapted to mesh with a centrally disposed pinion 74, which, as shown, is integral with the clutch member 25 above described. The clutch member 25 is preferably bored throughout although the inner bore 30 is of a smaller diameter and is adapted to guide a centrally disposed clutch actuating rod 77 having a threaded end 78 engaging a tube 79, the enlarged end 80 of which threadedly engages the piston 37. Near its outer end the rod 77 is provided with a pair of circumferential grooves 81 and 82 adapted to cooperate alternately with a spring pressed spherical detent 83 which is adapted to offer a certain resistance to relative axial movement between the rod 77 and clutch member 25, the amount of such resistance being predetermined according to the setting of the adjusting screw 85 threadedly engaging the transversely tapped opening in the clutch element 25 in which the said detent 83 is inserted.

Novel means for controlling the introduction of pressure fluid to the cylinder 15 and the automatic exhaust thereof as the piston 37 nears the end of its stroke, will now be described. In the preferred embodiment shown, such means includes a fluid pressure admission conduit 87 leading from any suitable reservoir or pressure generating chamber (not shown) such as the explosion chamber of a cartridge firing gun. The conduit 87 has a suitable connection 88 with a centrally disposed chamber 89 in the valve casing 90 threadedly engaging the centrally disposed boss 91 formed on the cylinder head 16. Mounted so as to be guided by said boss 91 is a fluted valve member 93 having an elongated stem 94 terminating in an enlarged end 95 adapted to be engaged and moved to the left as viewed in Fig. 1 by a striker disc 96 attached to the piston 37 by suitable means as indicated at 97. The valve 93 further includes a conical head 99 normally tending to be held from its seat on the counter-bored surface 100 provided in the valve casing 90 by a coiled compression spring 101, the pressure of which is adjustable through manipulation of an adjusting screw 102, the latter being centrally bored as indicated at 103 to permit escape of the actuating fluid to the atmosphere at the proper time as further explained hereinafter.

The means for relieving any excess operating pressure entering the cylinder preferably involves

the provision of a second valve casing 106 secured to the cylinder head 16 as indicated at 107 and having transverse and central openings, the central opening being provided with a check valve 109 normally held on its seat by a spring 110, the pressure of which is adjustable by the turning of an adjusting cap 111, which may be set to correspond to the desired maximum operating pressure, upon exceeding which the fluid forces the valve 109 from its seat and allows escape of the excess pressure through the transverse openings 112.

In operation, the entry of the actuating fluid into the valve chamber 89 operates to hold the valve 93 to its seat against the tendency of spring 101 and at the same time enter the cylinder 15 along the fluted surface of the valve, the pressure being then exerted over the entire exposed area of the piston 37 to force it to the left as viewed in Fig. 1. Since the piston is held from rotating by virtue of the provision of the splines 53, the screw action resulting from the thread 40 of the piston hub 39 and the threads of screw shaft 42, imparts a rotary movement to the latter member, which rotary movement is communicated to the gear 65. The gear 65 in turn drives the pinion 74 through the idler gears 69 while initial axial movement of the piston and corresponding axial movement of the tube 79 and rod 77 secured thereto has been effective to urge the clutch element 25 to the left to mesh the clutch teeth 25 with those of the engine member 26, the axial thrust being exerted upon the member 25 through the detent member 83. In the event the teeth of the members 25 and 26 abut during this forward movement, the detent 83 is pressed outwardly away from the groove 81 and then drops in the second groove 82 as soon as the forward movement of the rod 77 permits. In the interim, the continued rotary movement of the member 25 will relieve abutting condition and detent 83 again becomes effective (this time by virtue of its engagement with groove 82) to transmit the axial thrust on the rod to the engine engaging member to complete the meshing movement.

When the completion of this meshing movement prevents further forward motion of the driving member 25, the continued forward motion of the piston causes rod 77 to slide past the detent 83; and at the same time the application of the torque to member 25 through the gears 69 is effective to turn over the engine crankshaft to start the engine.

In this connection it will be noted that the cranking action thus exerted on the engine member 26 is a relatively rapid one due to the speed multiplying gear above referred to. Moreover such multiplied speed is obtained from the screw action of the piston without the necessity of employing any unusual excessive motion multiplying devices as multiple threaded sleeves, heretofore employed.

When the piston 37 has reached substantially the end of its power stroke, the resulting engagement of the collar 95 by the disc 96 moves the valve 93 from its seat 100 and thus allows the escape of the actuating fluid to the atmosphere by way of opening 103. After being thus opened, the valve remains open since the pressure on both sides thereof becomes substantially balanced and the spring 101 is accordingly effective to maintain the valve open until again moved to its closed position by the force of spring 48 acting through piston 37, sleeve 79 and enlarged end 95 of valve rod 94.

When the valve 93 has been opened as above de-

scribed, the spring 48 having been compressed by the forward movement of the piston, becomes effective to return the latter to its initial position as indicated in Fig. 1, the engine engaging-member 25 being at the same time withdrawn from the member 26 by the pull exerted thereon through the tube 79, rod 77 and detent 83.

The invention is not limited to the forms of construction which have been described, but can be carried out with all modifications based on the same principle, the arrangement comprising more than two screws, if desired. Such a starter can likewise be combined with an air compressor mounted on the same axis and driven by the motor shaft.

Likewise other changes which will now suggest themselves to those skilled in the art may be made in the form, details of construction and arrangement of the parts without departing from the scope of the invention as disclosed herein, and reference is therefore to be had to the appended claims for a definition of such scope.

What is claimed is:

1. In a device of the class described, in combination, an axially movable rotatable driven member, an axially movable non-rotatable driving member, a second rotatable member intermediate said driving and driven members, means for converting the axial movement of said driving member into rotary movement of said intermediate member, and means for temporarily releasing the driving connection between said driving and driven members, said means further acting to restore such driving connection after a predetermined, relatively slight degree of rotation of said driven member.

2. In a device of the class described, in combination, an axially movable rotatable engine-engaging member, an axially movable non-rotatable driving member, a second rotatable member intermediate said driving and engine-engaging members, means for converting the axial movement of said driving member into rotary movement of said intermediate member, means for transmitting a part of the axial movement of said driving member to said engine-engaging member, said last named means comprising a longitudinally movable member rigidly secured to said driving member and a yieldable connection between said longitudinally movable member and said engine-engaging member, means for temporarily releasing said yieldable connection to relieve a non-registering engagement between the longitudinally movable member and engine member, and means integral with said longitudinally movable member for restoring the effectiveness of said connection after the non-registering condition has been relieved.

3. In a device of the class described, in combination with an engine member, an axially movable rotatable driven member, an axially movable driving member, a second rotatable member intermediate said driving and driven members, means for converting the axial movement of said driving member into rotary movement of said intermediate member, means for transmitting a part of the axial movement of said driving member direct to said driven member to cause the latter to engage said engine member, said last named means comprising a rod rigidly secured to said driving member and yieldably connected to said driven member, means for causing relative axial movement between said driving and driven members to relieve a non-registering engagement between said driven member and the engine mem-

ber, and means integral with said rod for limiting the extent of said relative axial movement and thereafter causing additional axial movement of said driven member, after the non-registering condition has been relieved.

4. In a device of the class described, in combination with an engine member, an axially movable rotatable engine-engaging member, an axially movable driving member, a second rotatable member intermediate said driving and engine-engaging members, means for converting the axial movement of said driving member into rotary movement of said intermediate member, means for transmitting a part of the axial movement of said driving member to said engine engaging member to cause the latter to engage said engine member, speed multiplying means for transmitting all rotary movement of said intermediate member to said engine-engaging member, and means for temporarily releasing the driving connection between said driving and engine-engaging members to relieve a non-registering engagement between the latter and the engine member.

5. In a device of the class described, in combination with an engine member, an axially movable rotatable engine-engaging member, an axially movable driving member, a second rotatable member intermediate said driving and engine-engaging members, means for converting the axial movement of said driving member into rotary movement of said intermediate member, means for transmitting a part of the axial movement of said driving member to said engine-engaging member to cause the latter to engage said engine member, said last named means comprising a connecting member extending through said intermediate member and movable along the axis thereof, and means for temporarily releasing the driving connection between said driving and engine-engaging members to relieve a non-registering engagement between the latter and the engine member.

6. In a device of the class described, in combination, an axially movable rotatable engine-engaging member, an axially movable driving member, means for converting the axial movement of said driving member into rotary movement of said engine engaging member, means including a yieldable connection for transmitting a part of the axial movement of said driving member to said engine-engaging member, said last named means comprising a rod extending through said gear and movable along the axis thereof, and means integral with said rod and engaging said yieldable connection to continue the axial movement of said engine engaging member after a momentary interruption thereof.

7. In a device of the class described, in combination, an axially movable rotatable driven member, an axially movable driving member, a second rotatable member intermediate said driving and driven members, means for converting the axial movement of said driving member into rotary movement of said intermediate member, means for transmitting a part of the axial movement of said driving member to said driven member, said last named means comprising a rod actuated by said driving member and slidable within said driven member, a spring pressed detent mounted in said driven member in position to releasably engage said rod, and means on said rod for engagement with said detent to continue the axial movement of said driven member after momentary interruption thereof.
